UNITED STATES PATENT OFFICE.

JOSEPH WALDEN, OF ORANGE, NEW JERSEY.

DESIGN FOR A VAMP-STAY FOR SHOES.

SPECIFICATION forming part of Design No. 27,961, dated December 7, 1897.

Application filed September 11, 1897. Serial No. 651,383. Term of patent 14 years.

To all whom it may concern:

Be it known that I, JOSEPH WALDEN, a citizen of the United States, residing at Orange, in the county of Essex and State of New Jersey, have invented and produced a new and original Design for a Vamp-Stay for Shoes, of which the following is a specification, reference being had to the accompanying drawings, in which—

10 Figure 1 is a plan view; Fig. 2, an obverse; and Fig. 3 is a vertical cross-section.

The leading features of my design are the curved line 1, the chord 2, and the base-line 3, which is parallel with said chord, that portion of the vamp-stay which is bounded by

the chord 2 and its arc being the embossed portion, while the compressed portion of the stay is a zone bounded by the chord 2, the base-line 3, and those arcs of the curve 1 which are included between said chord 2 and 20 said base-line 3.

What I claim, and desire to secure by Letters Patent, is—

The design for a vamp-stay for shoes, as herein shown and described.

JOSEPH WALDEN.
